UNITED STATES PATENT OFFICE.

CHARLES E. MILLER, OF ANDERSON, INDIANA.

TUBE-SPlice VULCANIZER.

1,364,133.

Specification of Letters Patent. Patented Jan. 4, 1921.

Application filed July 26, 1920. Serial No. 399,109.

To all whom it may concern:

Be it known that I, CHARLES E. MILLER, a citizen of the United States, residing at Anderson, in the county of Madison and State 5 of Indiana, have invented certain new and useful Improvements in Tube-Splice Vulcanizers, of which the following is a specification.

This invention relates to tube splice vul- 10 canizers and it consists in the novel features hereinafter described and claimed.

An object of the invention is to provide a tube splice vulcanizer of simple structure which is adapted to effectually join the ends 15 of a rubber tube together when the same is intended to be used as the inner tube of a tire.

A further object of the invention is to provide a tube splice vulcanizer having its parts 20 and features so arranged and associated that the portions of the tube which lie adjacent the splice are not damaged or injured during the splicing operation.

A still further object of the invention is 25 to provide means for securely and accurately holding the parts of the tube in the proper adjusted positions with relation to each other during the splicing operation, so that the ends of the tube may be properly joined 30 together at the intended point or lines.

A still further object of the invention is 35 to provide an improved method for vulcanizing the spliced ends of a rubber tube which consists, essentially, in holding the ends of the tube in juxtaposition in the presence of heat externally applied and simultaneously expanding the ends of the tube from within and pressing them against a circumscribing abutment and without subjecting those por- 40 tions of the tube which are adjacent the splice to the damaging effects of the heat.

In the accompanying drawings:—

Figure 1 is a perspective view of the tube splice vulcanizer illustrating the end por- 45 tions of a tube held therein.

Fig. 2 is a longitudinal sectional view of the same.

Fig. 3 is a transverse sectional view of the same cut on the line 3—3 of Fig. 2.

Fig. 4 is a perspective view of a jacket used in the tube splice vulcanizer.

Fig. 5 is a perspective view of a block used in the device.

Fig. 6 is a perspective view of a mandrel 55 used in the same.

Fig. 7 is a perspective view of a bag used therein.

The tube splice vulcanizer comprises a mandrel 1 which is hollow and open at its ends. The said mandrel is cylindrical in transverse section. The mandrel is provided at its side with a longitudinally disposed slot 2 which extends from end to end of the mandrel. The slot 2 is provided at a point between the ends of the mandrel with an enlargement 3. A collar 4 is provided at one end of the mandrel and the said collar is rounded at the outer edge of its outer end as at 5. The slot 2 passes through the said collar.

The mandrel 1 is provided at a point between its ends with a second collar 6 and which is provided at its edge and at that face which is the more remote from the collar 4 with an outstanding flange 7. The slot 2 passes through the collar 6 and flange 7. The enlargement 3 of the slot 2 is located at a point approximately midway between the collars 4 and 6. The parts of the mandrel as hereinbefore described are preferably 80 integral or one body.

The tube splice vulcanizer also includes a bag or sack 8 which is adapted to be wrapped around the mandrel and lie between the collars 4 and 6 thereof. The bag 8 is made 85 preferably of rubber or similar expandible material and the said bag is closed at its ends and which are adapted to overlap each other when the bag is placed in position upon the mandrel, as described. The bag 8 is pro- 90 vided at its side and at a point between its ends with a nipple 9 which is adapted to pass through the enlarged part 3 of the slot 2 when the parts are assembled.

The nipple 9 is provided at a point be- 95 tween its ends with a bend whereby one end portion of the said nipple may extend along the mandrel and within the same and out at one end thereof. The said nipple may be connected with a source of air pressure (not shown) whereby air under pressure may be passed into the bag 8 and expand the same during the splicing operation as hereinafter described.

The tube splice vulcanizer further in- 105 cludes a steam jacket 10 which is hollow and arcuate in side elevation. The ends 11 of the jacket are juxtaposed with relation to each other and they are spaced apart and the surfaces of the said ends converge to- 110

ward each other from the central portion of the jacket to the peripheral portion thereof. The jacket is provided at its opposite sides and at the ends of the central opening thereof with outstanding flanges 12 which have spaced ends that lie in the same planes as those in which the ends of the body of the jacket lie. Therefore a passageway is provided through which a tube 13 may be 10 passed, sidewise, into the jacket and through which the said tube may be passed when the jacket is removed from the same.

The jacket is provided with a steam inlet port 14 which is located opposite the space 15 between the ends of the jacket, and the jacket is provided at its opposite sides with steam outlet ports 15.

Fig. 2 of the drawings shows the arrangement of the parts when in position for the 20 vulcanizing operation. To effect this arrangement one end portion of the tube 13 is collapsed and passed through the mandrel 1. The nipple 9 is then passed through the enlargement 3 of the slot 2 and is extended 25 along the collapsed portion of the tube 13 and extends out and beyond one end of the mandrel. The bag 8 is then wrapped around the mandrel and lies between the collars 4 and 6 of the mandrel. The tube 13 is then 30 opened and carried around the rounded end portion 5 of the collar 4 and is slipped back over the bag and the collar 6. The tube is then folded upon itself and carried toward that end of the mandrel at which the collar 35 4 is located so that the edge of the tube 13 lies approximately midway between the collars 4 and 6. The other end of the tube 13 is then passed over that portion of the said tube which is in position over the end of 40 the mandrel at which the collar 4 is located so that the end edges of the tube 13 come together. The block 16 is then removed from between the ends of the jacket 10 and the tube 13 is partially collapsed and passed 45 sidewise through the space between the ends of the jacket. The mandrel is then shoved into position within the jacket and the block is replaced in position between the ends of the jacket.

50 Assuming that the tube and the parts of the tube splice vulcanizer are assembled in the positions as shown in Fig. 2 of the drawings and that the operation of vulcanizing the ends of the tube together is about to begin. Steam is admitted into the jacket 10 through the inlet port 14 whereby the end portions of the tube 13 are heated. The flanges 12 at the sides of the jacket diffuse the heat at the end portions of the tube and 55 prevent damage to the tube in the vicinity of the splice. At the same time air is admitted through the nipple 9 into the bag 8 whereby the bag is expanded and the abutting ends of the tube are forced from within 60 against the inner surfaces of the jacket 10

and the block 16 whereby the ends of the tube are vulcanized together in the presence of heat applied from the exterior of the tube and from pressure applied from within the tube whereby it is expanded and 70 pressed against the said inner surfaces of the jacket and block. After the ends of the tube are spliced together and in order to remove the tube from the vulcanizer the method, as hereinbefore described setting 75 forth the manner of arranging the parts for the vulcanizing operation is reversed. Hence it will be seen that an improved and simplified method and apparatus for splicing the ends of a rubber tube by vulcanizing, is provided. 80

Having described the invention what is claimed is:—

1. In a tube splice vulcanizer a hollow jacket having a central opening and outstanding flanges located at the sides and at the ends of the opening. 85

2. In a tube splice vulcanizer a hollow jacket having spaced ends which are opposite each other and a block insertible in the space between the ends. 90

3. In a tube splice vulcanizer a hollow jacket having a central opening and spaced ends which are opposite each other, said jacket having outstanding flanges located at 95 its sides and at the ends of the opening.

4. In a tube splice vulcanizer a hollow jacket having a central opening and spaced ends which are opposite each other, a block insertible in the space between the ends. 100 said jacket also having outstanding flanges located at its sides and at the ends of the opening.

5. In a tube splice vulcanizer a hollow jacket having spaced ends which are opposite each other, a block insertible in the space between the ends and means for securing the block in position between the ends. 105

6. In a tube splice vulcanizer a hollow jacket having spaced ends which are opposite each other, a block insertible in the space between the ends and a stem screw threaded into the block and having a collar adapted to engage the jacket. 110

7. In a tube splice vulcanizer a hollow jacket having spaced ends with converging opposite surfaces, and a wedge shaped block insertible in the space between the ends and adapted to engage the said converging surfaces. 115

8. In a tube splice vulcanizer a hollow jacket having spaced ends with converging opposite surfaces, a wedge shaped block insertible in the space between the ends and adapted to engage the said converging surfaces and a stem having screw thread engagement with the block and having a collar adapted to engage the jacket. 125

9. A tube splice vulcanizer comprising a mandrel, an inflatable bag located thereon 130

and a jacket for receiving the mandrel and bag.

25

10. A tube splice vulcanizer comprising a mandrel provided with a slot, an inflatable bag located upon the mandrel and having a nipple which passes through the slot and a jacket receiving the mandrel and bag.

11. A tube splice vulcanizer comprising a mandrel having spaced collars, an inflatable bag located on the mandrel between the collars and a jacket for receiving the mandrel and bag.

12. A tube splice vulcanizer comprising a mandrel having spaced collars and a longitudinally disposed slot, an inflatable bag located upon the mandrel between the collars and having a nipple which passes through the slot and a jacket for receiving the mandrel and bag.

13. In a tube splice vulcanizer a mandrel having a slot, a jacket adapted to receive the mandrel and a bag having closed ends and adapted to wrap upon the mandrel and hav-

ing a nipple adapted to pass through the slot.

30

14. In a tube splice vulcanizer a mandrel having a slot, and a bag adapted to wrap upon the mandrel and having closed ends, said bag being provided at a point between its ends with a nipple which passes through the slot.

15. A tube splice vulcanizer comprising a mandrel, a jacket adapted to receive the mandrel and a tube expanding member located upon the mandrel and within the jacket.

35

16. The method of splicing the ends of a rubber tube which consists in holding the ends of the tube in juxtaposition in the presence of heat externally applied and simultaneously expanding the ends of the tube from within and pressing them against a circumscribing abutment.

40

In testimony whereof I affix my signature.

CHARLES E. MILLER.
